UNITED STATES PATENT OFFICE.

JOHN W. BENNETT, OF HALIFAX, NOVA SCOTIA, CANADA.

STENCIL-HOLDER.

SPECIFICATION forming part of Letters Patent No. 308,457, dated November 25, 1884.

Application filed November 17, 1883. (Model.)

To all whom it may concern:

Be it known that I, JOHN W. BENNETT, of 5
Halifax, Nova Scotia, Canada, have invented a
new and useful Improvement in Stencil-Hold-
ers; and I do hereby declare that the follow-
ing is a full, clear, and exact description of
the same, reference being had to the accom-
panying drawings, forming part of this speci-
fication, in which—

10 Figure 1 is a plan view of the device. Fig.
2 is a vertical longitudinal section through the
line $x-x$ of Fig. 1. Fig. 3 is a plan view of
the lower frame and stencil-plates, the upper
or hinged frame being raised; and Fig. 4 is a
15 transverse section through the line yy of Fig. 1.

My invention has for its object to provide
a device for holding a number of stencil-plates
in the order of their arrangement to form a
word or name, and securing them in such re-
20 lation while the brush is being used to make
the letters through the same.

To this end it consists in the peculiar con-
struction and arrangement of two clamp
25 plates or frames for holding the stencil-plates,
and means for fastening said plates together
and preventing the stencil-plates from mov-
ing laterally, as will be hereinafter fully de-
scribed.

In the drawings, A represents the upper
30 and B the lower clamp-plates, which at one
side or end are hinged together, as at a.

As shown, the clamp plates or frame is con-
structed for two rows of stencil-letters; but
it may only accommodate a single row, and
35 in many instances will be so constructed.
The two plates are provided with suitable
stiffening-ribs, b for the upper plate and c for
the lower plate, to prevent the frame from
bending. The latter, however, are not an es-
40 sential feature, and may be dispensed with.

C are the stencils or letter-plates, which, for
adaptation to my frame, are provided at the
ends with upturned flanged ends d, (see Fig.
4,) offset from the plane of the letter or body
45 section, which upturned and offset flanges
rest upon the top surface of the inner mar-
gin of the lower frame-plate, B, while their
middle parts, having the stencil-letters through
them, descend to a point flush with or a lit-
50 tle below the stiffening-ribs c on the lower
side of the bottom plate, so as to rest flat upon

the object upon which the letters are to be
marked. The stencil-letter plates of each row
are forced into close adjacent contact at their
edges by a sliding check-plate, D, whose edge 55
next to the stencil-letters is turned down to
the plane of the body portion of the letters,
and which plate, when forced up against the
row of stencil-letters, is tightly held at such
point by a set-screw, E. This check-plate is 60
guided in its adjustment by a slot, e, which
surrounds its set-screw, and also by a cleat or
overhanging plate, f, Fig. 3. In the place of
this means for guiding and holding it, how-
ever, the plate may be arranged to work in a 65
groove or guide-pin; or lugs may be employed.
For operating this slide, a small knob, g, is
attached to the outer end thereof. After the
stencil-letters are placed in the frame in proper
order, they are clamped between the upper 70
and lower frame by turning the hinged frame
A down upon its flanges, which being done,
the upper plate is secured to the lower one by
a sliding locking-plate, F, on the upper side of
plate A, which locking-plate has bolts h h, that 75
catch beneath upright hasps or keepers i i, at-
tached to the lower plate. When the frame
is arranged for two rows of letters, as shown,
this locking-plate is made T-shaped, and its
middle or shank portion slides between the 80
middle guide-ribs, b b. Said locking-plate is
forced outwardly to lock its bolts into the
keepers by the spiral spring j, which is wound
around a rod attached to said shank, and
bears against lug n. Said plate is withdrawn 85
by a thumb-piece, k, and when it is with-
drawn it is held back by a small bolt, l, car-
ried by a flat spring, m, which latter forces
the bolt l into a hole in the top of plate A.

To lift and handle the stencil-holder, a ver- 90
tical handle, G, is fixed to the middle of the
top frame, A; and passes through a slot in
the shank of the T-shaped locking-plate.

In modifying my invention I may, instead
of hinging the plates at one side, make them 95
entirely detachable and provide locking de-
vices at both ends.

Having thus described my invention, what I
claim as new is—

1. The combination, with a stencil-holder 100
constructed with two separable slotted plates
or frames, of an adjustable check-plate held

between the frames and provided with means for locking it in the desired position, substantially as herein shown and described.

2. The combination, with a stencil-holder constructed with two hinged slotted plates or frames, of a check-plate held on the lower hinged plate to slide in the direction of the length of the same, and a binding-screw for locking the sliding check-plate in place.
- 10 3. In a stencil-holder, the combination, with the plates A B, hinged to each other, of the screw E, substantially as herein shown and described.

4. In a stencil-holder, the combination, with the hinged plates A B, of the screw E and the sliding check-plate D, substantially as herein shown and described. 15

5. In a stencil-holder, the combination, with the hinged plates A B, of the spring-actuated locking-plate F, with bolts *h*, and the keeper *i*, substantially as herein shown and described. 20

JOHN W. BENNETT.
